UNITED STATES PATENT OFFICE.

COLEMAN J. MANNING, OF MEDFORD, MASSACHUSETTS.

ATTACHMENT FOR FAUCETS, &c.

1,071,165.

Specification of Letters Patent. Patented Aug. 26, 1913.

Application filed October 4, 1911. Serial No. 652,867.

To all whom it may concern:

Be it known that I, COLEMAN J. MANNING, a citizen of the United States, and a resident of Medford, in the county of Middlesex and State of Massachusetts, have invented certain new and useful Improvements in Attachments for Faucets, &c., of which the following is a specification.

This invention is embodied in a conduit 10 adapted to be flexibly and detachably coupled to the faucet of a wash-bowl or lavatory and to conduct the stream of water issuing from the faucet for the purpose of utilizing said stream in different ways, as 15 for example, in inducing a flow of air through a massage applicator, as shown by Letters Patent of the United States No. 946,972, granted to me January 18, 1910.

The invention has for its object, first, to 20 provide means for conveniently varying the volume of air drawn through a massage applicator by a stream of liquid flowing through the conduit, secondly, to enable the conduit to be used if desired as a means for 25 conducting water, from the faucet to which it is coupled, to a spraying nozzle, and thirdly, to provide improved means for coupling the conduit to the faucet.

The invention consists in the improvements 30 which I will now proceed to describe and claim.

Of the accompanying drawings which form a part of this specification,—Figure 1 represents a longitudinal sectional view of a conduit embodying my invention, Fig. 2 represents a side view of the detachable seat 35 hereinafter referred to.

Similar reference characters indicate the same or similar parts in all the figures.

40 My improved conduit which is adapted to be coupled as stated to the discharge nozzle of a faucet, comprises an enlarged bell shaped receiving portion 12, a contracted internally threaded portion 13, a delivering portion 14 having a contracted bore 15 which is enlarged at its inner end to form a cup 16, an intermediate portion 17 which is integral with the contracted portion 13 and is internally threaded at one end to engage 45 an external screw thread on the delivering portion 14, the portion 17 forming a chamber 17^a between the portions 12 and 14, a nozzle 18 externally threaded at one end to engage the internal thread of the portion 13 50 and provided with a contracted bore 19 extending through its opposite end which pro-

jects into the cup 16, and a nipple 20 which enters one side of the portion 17 and communicates with the chamber formed thereby. The parts above described are so formed and 60 relatively arranged that a stream of water under pressure flowing through the conduit, the nozzle portion 14 being open, will induce an inward flow of air through the nipple 20 and through a massage applicator connected 65 by a flexible tube with said nipple.

The screw-threaded connection between the nozzle 18 and the conduit portion 13 enables the nozzle to be adjusted lengthwise to vary its distance from the bottom of the cup 70 16 and thus increase or diminish the volume of air drawn through the nipple 20, the nozzle being provided with slots 21 adapted to be engaged by a screw driver.

The delivering portion 14 is provided 75 with a cock 22 which may be turned to close said portion and cause water passing through the nozzle 18 to pass outwardly through the nipple 20 and through a spraying device which may be connected therewith by a flexible tube. When the conduit is used in this way the nozzle 18 is adjusted to permit the maximum freedom of movement of water from it through the chamber 17^a and nipple 20. When the conduit is 80 used to create a vacuum, as above described, the cock 22 is left open. The enlarged end of the receiving portion 12 is provided with an external screw thread 23 and with a recess 24 which is surrounded by the screw 85 thread.

25 represents an annular seat which is a flat sided ring, the margin of which is adapted to enter the recess 24, the thickness of the seat being such that its upper surface 90 is flush with the edges of the portion 12 surrounding the recess 24.

26 represents an elastic rubber coupling tube which is adapted to receive and be expanded by a faucet and is provided with an 100 outwardly projecting elastic flange 27 formed to bear on the outer side of the seat 25 and to overlap the edge of the conduit portion 12.

28 represents a confining cap or clamp 105 having an internally threaded flange 29 adapted to engage the external thread 23. The clamp 28 has a central opening 30 to receive the faucet.

The seat 25 constitutes a practically rigid 110 support for the flange 27 and supports the latter against the pressure of the confining

- clamp 28. When said clamp is screwed down upon the conduit it compresses the flange so that leakage of water between the seat and the portion of the conduit on which it bears is prevented. The seat prevents the coupling tube 26 from being forced inwardly into the portion 12 of the conduit by the pressure employed in applying the coupling tube to the faucet.
- 10 The coupling tube 26 is of considerably smaller diameter than the interior of the receiving portion 12 so that a chamber 12^a is formed around the coupling tube. The liquid entering said chamber is obstructed 15 by the nozzle 18 so that there is considerable back pressure in the chamber 12^a, this pressure holding the coupling tube 26 firmly against the faucet.
- I claim:—
- 20 1. An attachment for faucets, comprising a conduit having an enlarged bell-shaped receiving portion, a contracted internally threaded portion below said receiving portion, an enlargement below said threaded portion, a discharge nipple, a lateral nipple communicating with said enlargement, and a nozzle externally threaded and engaging the internally threaded contracted portion and extending through said enlargement 25 and across the inner end of the lateral nipple.
2. An attachment for faucets, comprising a conduit having an enlarged bell-shaped receiving portion, a contracted internally threaded portion below said receiving portion, an enlargement below said threaded 30 portion, a discharge nipple, a lateral nipple communicating with said enlargement, and a nozzle externally threaded and engaging the internally threaded contracted portion and extending through said enlargement and across the inner end of the lateral nipple.
- 35

portion, a discharge nipple, a lateral nipple communicating with said enlargement, and a nozzle externally threaded and engaging the internally threaded contracted portion 40 and extending through said enlargement and across the inner end of the lateral nipple, the discharge nipple being provided with a cock whereby it may be closed to cause the discharge of liquid through the 45 lateral nipple.

3. An attachment for faucets, comprising a conduit having an enlarged bell-shaped receiving portion and a contracted internally threaded portion below said bell-shaped portion, a nozzle externally threaded to engage the internal threads of the contracted portion and having means whereby it may be rotated to adjust the same in the direction of its length, an elastic coupling 55 having a tubular portion in substantial alignment with the nearer end of the adjustable nozzle whereby an implement may be inserted through said tubular portion to adjust the said nozzle, a chamber through 60 which said nozzle passes, and a nipple communicating with said chamber whereby a flow of liquid through said adjustable nozzle may be utilized to induce a flow of another fluid through said nipple. 65

In testimony whereof I have affixed my signature, in presence of two witnesses.

COLEMAN J. MANNING.
